UNITED STATES PATENT OFFICE.

GEORGE L. ALLEN, OF WORCESTER, MASSACHUSETTS.

APPARATUS FOR EXTRACTING DYES.

SPECIFICATION forming part of Letters Patent No. 274,891, dated April 3, 1883.

Application filed October 14, 1882. (No model.)

To all whom it may concern:

Be it known that I, GEORGE L. ALLEN, of Worcester, in the county of Worcester and State of Massachusetts, have invented certain new and useful Improvements in Apparatus for Extracting Dyes; and I declare the following to be a description of my said invention sufficiently full, clear, and exact to enable others skilled in the art to which it appertains to make and use the same, reference being had to the accompanying drawings, which form a part of this specification.

The object of my present invention is to render the apparatus more convenient, efficient, and desirable for use.

One feature of my invention relates to the construction and arrangement of devices for supporting the perforated diaphragm to permit of the ready and convenient removal and replacement of the parts thereof.

Another feature of my invention relates to the manner of constructing and arranging the strainer in connection with the lower pipe-aperture.

Another feature of my invention relates to the combination of devices for closing the feeding and discharge openings in a manner to give tight and perfect connections while permitting ready access to the interior.

Another feature of my invention relates to the introduction of steam circumferentially to the interior of the keir above the false bottom or perforated diaphragm.

The peculiarities of construction and particular subject-matter claimed are hereinafter definitely specified.

In the drawings Figure 1 is a part side, part sectional view of a dye-extractor, illustrating the nature of my invention. Fig. 2 is a horizontal section at line $x-x$, showing a portion of the diaphragm removed to reveal parts beneath. Fig. 3 shows a side view of the supporting-standard, with sectional parts of the diaphragm and head, and views of the collar and key separate from the standard. Fig. 4 shows a plan and side of one of the diaphragm-segments. Fig. 5 is a sectional view through one side of the closing-plate and its supporting devices.

On the drawings, A denotes the body or shell of the keir, which is made substantially in the ordinary form, with upper and lower

heads, A' A', to which are respectively connected the escape pipe B and the draw-off pipe C for supplying steam to the interior and for drawing off the dye-liquid. Openings with doors D for the introduction and discharge of the dye wood or material are arranged in the side of keir at the usual positions. The position of lower opening is indicated in Fig. 2 by dotted lines.

E indicates the false bottom, grating, or perforated diaphragm, arranged for supporting the solid portions of the dye material while permitting the draining off of the liquid. Said diaphragm is made of a number of removable sections, e, of the form indicated in Figs. 2 and 4, and of such size that they can be passed through the door-opening. The outer ends of the sections e are supported by a rim or flange, F, attached to the inner surface of the shell A, while above this rim F, at a distance corresponding with the thickness of the sections e, is a second or upper rim, G, attached in similar manner to the shell A, and which serves to prevent the sections e from being forced upward, the edges of the diaphragm being thus securely retained between the rims F and G. The rim G does not pass across the door-space, but extends over the corners of the last section e sufficiently far to retain it in position.

I indicates the standard for supporting the center of the diaphragm or inner ends of the perforated sections e. The foot of the standard I, which rests upon and is connected with the head A', is made furcated to span the opening and strainer of the pipe C. The upper part of the standard I is made with a flange or shoulder, i, upon which the sections e rest, and with a central stud projecting above the sections to receive the locking devices. A collar or ring, J, is arranged to slip over the end of the standard, and a key, K, is passed through the end of the stud above said collar, thereby securing all of the diaphragm-sections in position. For removing and replacing the diaphragm E it is simply necessary to knock out the key K and slip off the collar J from the standard. Then by raising the inner ends of the sections e they can be released from the rims F G and passed one at a time through the door-opening, the operation being readily and conveniently effected, so that no trouble

is experienced in obtaining access to the lower chamber of the apparatus.

L indicates a perforated spherically-arched plate or strainer arranged over the end of the pipe C, within the lower chamber of the keir and beneath the furcated standard I. This strainer, by reason of its spherical form, serves to distribute the entering steam within the chamber in a very thorough and satisfactory manner beneath the diaphragm E. The strainer-plate L may be secured to the head by rivets or bolts; or it may be detachably secured thereto, so as to permit its ready removal after the diaphragm has been taken out. A convenient method of fastening it to place is to wedge it beneath grooves or lugs formed on the feet of the furcated standard I. The segments e are preferably provided with small knobs or pins on their edges, which facilitate fitting them together, and retain them with their edges slightly separated. The rim G forms a closing-joint about the circumference of the diaphragm, and obviates the necessity and labor of accurately fitting the outer edges of the several segments e.

The upper and lower doors, D and D', are of similar construction. The door-frame D² is provided with a groove containing soft metal, rubber, or other suitable packing material, P, and is furnished with ears projecting from its sides, as indicated. The door-plate D is provided with projecting arms d, furcated at their outer ends to receive the clamping-screws M, which are hinged to the door-frame D², as shown at m, Fig. 5, so as to swing back out of the way, as indicated by dotted lines, Fig. 5, or to swing up into the forks of the arms in position to permit of the door being clamped to its seat by the hand-wheel nuts N, screwed down onto the ends of the arms d, as illustrated. The door is hinged at one side, h, so as to swing back to one side of the frame D² when opened. The face of the door-plate is provided with a sharp angular flange or rib, S, to match the packing P of the door-frame, which flange is indented into said packing when the door is forced against its seat, and a close-fitting, tight joint is thus formed to prevent the escape of steam or liquid around the doors.

50 t t t indicate cocks for determining the level and quality of liquid within the keir.

V indicates a coil of perforated steam-pipe, arranged around the interior of the shell at a position intermediate to the height of the keir, 55 or above the lower or discharge door, D'. Said pipe V is connected with the steam-supply,

and serves for conveying steam to the interior of the keir, in addition to the supply from pipe C, and delivering it circumferentially, or near the shell A, into the mass of dye wood or material, the object and result being to greatly enhance the boiling capacity of the apparatus and to effect an important reduction in the time required for extracting the charge of dye-stuffs. The coil V may be carried once or more 65 around the circle of the shell, as desired.

The general process of extracting the dyes with my apparatus, being substantially similar to the usual well-known method with apparatus of this class, need not be herein particularly described.

It will be understood that I do not herein make claim, broadly, to a dye-extractor having a diaphragm and upper and lower doors located in relation to the shell at the positions 75 indicated, as I am aware that extractors of this class have heretofore been in use.

What I claim as of my invention, and desire to secure by Letters Patent, is—

1. The standard I, provided with a shoulder, 80 i, for supporting the diaphragm, and having a furcated foot for spanning the pipe-aperture, as set forth.

2. The combination of the body or shell provided with upper and lower internal rims or 85 flanges, F G, the perforated segmental diaphragm E, the central furcated standard, I, having the flange or shoulder i, the collar J, and the key K, substantially as and for the purposes set forth.

3. In a dye-extractor, the combination, with the body A, of the door-frames D², having the recessed flange containing packing material P, and the hinge-ears at m, the door D, provided with the angular face-flange S and 95 projecting bifurcated arms d, the swinging screws M, and hand-wheel nuts N, said parts being arranged as shown, and for the purposes set forth.

4. The combination, as described, of the 100 bottom head A', the pipe C, the perforated diaphragm E, the furcated supporting-standard I, and the spherically-arched strainer L, secured between the feet of said standard, all in the manner shown, for the purposes set 105 forth.

Witness my hand this 4th day of October,
A. D. 1882.

GEORGE L. ALLEN.
